DESIGN FOR A BASS SECTION OF AN ACCORDION OR SIMILAR ARTICLE

Mario Soprani, Castelfidardo, Italy, assignor to Continental Music Company, Inc., Chicago, Ill.,
a corporation of Illinois

Application December 29, 1939, Serial No. 89,207

Term of patent 14 years

To all whom it may concern:

Be it known that I, Mario Soprani, a subject of the King of Italy and residing in Castelfidardo, Province of Ancona, Italy, have invented a new, original, and ornamental Design for a Bass Section of an Accordion or Similar Article, of which the following is the specification, reference being had to the accompanying drawing, forming a part thereof.

On the drawing:

Figure 1 is a perspective view of the bass section of an accordion or similar article, showing my new design.

I claim:

The ornamental design for a bass section of an accordion or similar article, as shown.

MARIO SOPRANI.
